CONTROL SYSTEM

William A. Ray, Los Angeles, Calif.

Original application May 14, 1940, Serial No. 335,085. Divided and this application April 19, 1943, Serial No. 483,544

5 Claims. (Cl. 236—84)

This invention relates to control systems for fluid-fuel consuming heating apparatus; the present application being a division of my co-pending application, Serial No. 335,085, filed May 14, 1940, now Patent 2,317,639, dated April 27, 1943.

An object of this invention is to provide—in a burner control system comprising electrically-controlled valve means adapted to supply fuel to a main burner in such amounts that either a low-fire or a high-fire condition thereat can be established—a pair of thermoelectric generating devices for energizing the valve means; one of these devices being arranged to be heated by the main burner, and the other by a supplemental burner.

Another object is to provide a system, of the character described in the preceding object, wherein one of the thermoelectric generating devices is heated by a continuously-burning pilot burner for the main burner and is capable of providing energy to the valve means in an amount such that thereby a low-fire condition can be established; the other thermoelectric generating device, heated by the main burner, being capable of providing an amount (or, additional amount) of energy sufficient for the establishment of the high-fire condition.

Other objects and advantages of the invention will be found in the description, the drawing, and the claims; and, for full understanding of the invention, reference may be had to the following detailed description and accompanying drawing, wherein:

Figures 1, 2 and 3 are diagrammatic views of a valve, of a type adapted for use in connection with the thermoelectric generating means of my invention, and including an electrical control system; the parts being shown in the several views in the positions which they assume in operation; and

Figure 4 is a diagrammatic view of a thermoelectric system, embodying this invention, adapted for the control of the valve shown in Figs. 1-3.

Referring first to Figs. 1, 2 and 3 of the drawing, the numeral 15 indicates a valve casing having an inlet 16 and an outlet 17 separated by a partition 18. This partition has a main port opening 19 therethrough, provided at its upper and lower ends, respectively, with valve seats 20 and 21. A flexible diaphragm 22, covering an opening in the top wall of the valve casing, carries a closure member 23 provided with an upper 24 and a lower 25 valve member cooperable, re-

spectively, with the seats 20 and 21. Defining, with the valve casing, a pressure chamber 26 above the diaphragm 22, is a housing 27. Secured to the top of this housing, and defining therewith another chamber 28, is another housing 29.

Mounted in the chamber 26 is a first electromagnetically operated pilot valve 30 comprising a pivoted armature 31, the upper end portion of which serves as a closure member for jets 32 and 33, which are connected respectively by pipes 34 and 35 with the inlet 16 and the chamber 28. The armature is normally held in engagement with jet 33 by the force of a spring 36 and is movable, when core 37 is energized by current flow in coil 38, into engagement with the other jet 32. Mounted in the chamber 28 is a second electromagnetically operated pilot valve 39, similar to the pilot valve 30, and comprising a pivoted armature 40, the upper end portion of which is cooperable with jets 41 and 42 which are connected respectively by pipes 43 and 44 with a passageway 45 formed in the partition 18 and communicating with the port 19, and with the atmosphere. The armature is biased by a spring 46 into engagement with the jet 41 and is movable, when core 47 is energized by current flow in coil 48, into engagement with the jet 42.

A thermostat suitable for automatic control 30 of the valve comprises a bimetallic member 49 which carries a contact element 50 cooperable with a fixed contact 51 connected to one terminal of the coil 48. Secured to the bimetallic member is a resilient arm 52 which carries another 35 contact element 53 cooperable with another fixed contact 54 connected to one terminal of the coil 38. The other terminals of the coils are connected together and to the bimetallic member through a source of current 55. The contacts are 40 so arranged that, in the anticlockwise movement of the bimetallic member from the position shown in Fig. 1, engagement of the elements 53 and 54 is effected before that of elements 50 and 51; the resilience of the arm 52 permitting the subsequent additional engagement of the latter pair. Similarly, when the bimetallic member subsequently moves in the opposite direction, elements 50 and 51 are disengaged before elements 53 and 54.

50 Assuming that the valve shown in Figs. 1-3 is connected to supply gas to the burner of a furnace for heating a space wherein the thermostatic member 49 is located, with the parts in the positions shown in Fig. 1, flow through the valve 55 is completely obstructed by the valve member 24

which is maintained by gravity in engagement with the seat surrounding the inlet end of port 19; fluid pressure above and below the diaphragm 22 being equalized by the open jet 32 of pipe 34, and the chamber 26 being closed from the atmosphere by the engagement of the armature with jet 33.

On cooling, the bimetallic member 49 moves in an anti-clockwise direction and thus, if the temperature in the space falls, the contacts 53 and 54 engage and current flows in coil 38, energizing the core 37 to attract the lower end of the armature which assumes the position shown in Fig. 2. Jet 32 now being closed and jet 33 open, the fluid which was compressed in chamber 26 escapes to the atmosphere through pipe 35, chamber 28 and pipe 44, as indicated by the broken arrows in Fig. 2. The pressure of the fluid in the inlet 16 can now force the diaphragm upward, the closure member assuming the position shown in Fig. 2 with the valve member 25 in engagement with the lower or outlet end of the port 19. In this position of the closure member, fluid can flow to the burner through a restricted passageway 56 formed in the partition 18 and interconnecting the port 19 and the outlet 17. A "low-fire" condition thus now exists at the burner, it being assumed that the fuel was ignited by a continuously burning pilot burner or other igniting means.

It will be noted that the closure member, in passing from the position shown in Fig. 1 to that shown in Fig. 2, passed through an intermediate position (shown in Fig. 3) wherein both ends of the port 19 were open. A momentary high flow of fuel to the burner was thus permitted which ensured proper and complete ignition.

If, in spite of the low-fire condition of the furnace burner, the space continues to cool, the bimetallic member will move farther, effecting engagement of contacts 50 and 51 in addition to that of contacts 53 and 54. The core 47, thus being energized, magnetically moves the armature 40 to the position shown in Fig. 3 wherein jet 41 is open and jet 42 closed. Fluid can now flow, as indicated by the broken arrows in Fig. 3, from the relatively high pressure zone existing in port 19 (the lower end of which is closed) through passageway 45, pipe 43, open jet 41, chamber 28 (which is now closed from the atmosphere), pipe 35, and open jet 33 into the pressure chamber 26 above the diaphragm which was previously at atmospheric pressure. The resultant increase in pressure above the diaphragm, opposing that below it, permits the closure member to fall to the intermediate position shown in Fig. 3 wherein it is balanced by the pressures and its weight. The factor controlling the balance is the pressure drop across the upper end of port 19 which increases as the member 26 approaches the seat 29. The resistance of the jet openings, which in practice are preferably quite small, has no effect on the final balance of the closure member, as the pressure is then static.

In the balanced position of the closure member, full flow through the valve is permitted to effect a "high-fire" condition at the burner. If the temperature in the space now rises, the thermostatic member will move in a clockwise direction to first open contacts 50 and 51, with the result that armature 40 will be released, closing jet 41 and opening jet 42. The compressed fluid can then escape from the chamber 26 to the atmosphere and the closure member will reassume its

"low-fire" position as shown in Fig. 2. Under normal heating conditions, the valve will be operated intermittently between its low- and high-fire positions. Should the temperature in the space rise above a predetermined degree, both pairs of thermostat contacts will open, deenergizing pilot valve 30 and thus subjecting the chamber above the diaphragm to the full pressure of the fluid to completely shut-off fuel supply to the burner.

Referring now to Fig. 4—wherein the thermoelectric system of this invention is shown arranged for the control of the valve disclosed in Figs. 1-3, when the same is employed to control fuel supply to a gas-consuming heating apparatus—the numeral 68 indicates a bimetallic member, responsive to the result of the heating, and carrying a first contact element 61, cooperable with a fixed contact 62. Secured to the bimetallic member is a resilient arm 63 which carries a second contact element 64, cooperable with another fixed contact 65. The fixed contact 65 is connected by a wire 66 to one terminal of an electromagnet coil 67, the other terminal of which is connected by a wire 68 to one terminal of a thermoelectric generating device or thermopile 69 which is so arranged as to be heated by the flame of a pilot burner 70 for a main burner 71. Similarly, the fixed contact 62 is connected by a wire 72 to one terminal of another electromagnet coil 73, the other terminal of which is connected by a wire 74 to one terminal of another thermopile 75 which is arranged to be heated by the flame of the main burner 71. The other terminals of the thermopiles are connected together by a wire 76, and to the bimetallic member by wire 77. Adapted to be energized respectively by current flow in the coils 67 and 73 are U-shaped cores 78 and 79 with which jet-controlling armatures 80 and 81 are respectively cooperable.

The jets with which armature 80 cooperates correspond to the jets 32 and 33 of the valve shown in Figs. 1-3 and serve to control the initial operation of the main closure member from closed to "low-fire" position when contacts 64 and 65 engage with fall of temperature at the bimetallic member. Current for the operation of this armature is provided by the thermopile 69 which is heated by the flame of the continuously burning pilot burner 70. The system is therefore always in condition for initial operation. When the main burner is in "low-fire" condition, the other thermopile is heated and current is then available for the operation of the other armature 81, which cooperates with jets corresponding to those shown at 41 and 42 in Figs. 1-3, and serves to control the operation of the closure member from low- to high-fire position when contacts 61 and 62 additionally engage. By this arrangement, the system is always ready for operation with minimum consumption of fuel for current generating purposes. If the pilot burner flame is accidentally extinguished, armature 80 is released and the main valve closes and cannot be reopened until the pilot burner is relighted, thus rendering the system "safe."

Another advantage of the arrangement shown in Fig. 4 resides in the fact that, when both of the pairs of thermostat contacts are engaged and thus both of the pilot valve operators energized, the thermostat is connected across points of equipotential in the circuit and therefore no current flows through the bimetallic member and

wire 71; it being assumed that the thermopiles are connected in series, as shown, and that their generated E. M. F.'s are equal, and also that the resistances of the coils, and of the branch circuits, are equal. The circuit then corresponds to a form of balanced Wheatstone bridge circuit, with the thermostat connected in the position usually taken by a null indicator. If a common source of current is employed, as in the circuit shown in Figs. 1-3, when both of the electromagnets are energized current passes through the bimetallic member in an amount equal to the sum of the currents through the two coils; whereas by the arrangement shown in Fig. 4, current flows only in the outer circuit and none (or a small amount, depending on the degree of balance of the bridge arms) passes through the bimetallic member.

The system of Fig. 4 is obviously adapted for the control of "high-low" valves other than of the type disclosed in Figs. 1-3; or of valves of the "modulating" type, wherein additional electrical energy is required for full opening of the valve. Further, if the electric valve-operator is sufficiently sensitive, it can be employed for "direct" control of fuel to the burner, i. e., without the requirement for auxiliary pressure-operated means. I wish it to be understood that still further modifications may be made without departing from the spirit of the invention, and that I intend therefore to be limited only by the scope of the appended claims.

I claim as my invention:

1. In a system for controlling the operation of a fluid-fuel consuming heating apparatus: a main burner; a supplemental burner; electrically controlled valve means for supplying fuel to said main burner in amounts sufficient to produce a low-fire or a high-fire condition thereat, said valve means requiring a predetermined amount of electrical energy in order to produce said low-fire condition and a greater amount in order to produce said high-fire condition; a first thermoelectric generating device of limited capacity, heated by the flame of said supplemental burner, for supplying only said predetermined amount of energy to the valve means; and a second thermoelectric generating device, heated by the flame of said main burner, for supplying to said valve means energy in an amount sufficient for the establishment of said high-fire condition; the flame of said supplemental burner being so small that it is incapable of effectively heating both of said thermoelectric generating devices.

2. In a system for controlling the operation of a fluid-fuel consuming heating apparatus: a main burner, a supplemental burner, first electrically controlled valve means for supplying fuel to said main burner in an amount sufficient to produce a low-fire condition thereat, a first thermoelectric generating device heated by the flame of said supplemental burner for energizing said first valve means, second electrically controlled valve means for supplying fuel to said main burner in such amount that a high-fire condition is established thereat, and a second thermoelectric generating device heated by the flame of said main burner for energizing said second valve means, the amount of energy produced by said first thermoelectric generating device being insufficient for both of said valve means and the flame

of said supplemental burner being so small that it is incapable of effectively heating both of said thermoelectric generating devices.

3. In a system for controlling the operation of a fluid-fuel consuming heating apparatus: a main burner; a continuously-burning pilot burner for said main burner; electrically controlled valve means for supplying fuel to said main burner in amounts sufficient to produce a low-fire or a high-fire condition thereat, said valve means requiring a predetermined amount of electrical energy in order to produce said low-fire condition and a greater amount in order to produce said high-fire condition; a first thermoelectric generating device of limited capacity, heated by the flame of said pilot burner, for supplying only said predetermined amount of energy to the valve means; a second thermoelectric generating device, heated by the flame of said main burner, for supplying to said valve means energy in an amount sufficient for the establishment of said high-fire condition; the flame of said pilot burner being so small that it is incapable of effectively heating both of said thermoelectric generating devices; and means, movable in response to change in a condition resulting from the operation of said main burner, for controlling the energization of said valve means by said thermoelectric generating devices.

4. A control system, as defined in claim 3, wherein said condition responsive means is effective, in the movement thereof in one direction, to first effect energization of said valve means by said first thermoelectric generating device, and, by continued movement in the same direction, to effect energization of the valve means by said second thermoelectric generating device.

5. In a system for controlling the operation of a fluid-fuel consuming heating apparatus: a main burner; a continuously-burning pilot burner for said main burner; first electrically controlled valve means for supplying fuel to said main burner in an amount sufficient to produce a low-fire condition thereat; a first thermoelectric generating device, heated by the flame of said pilot burner, for energizing said first valve means; second electrically controlled valve means for supplying fuel to said main burner in such amount that a high-fire condition is established thereat; a second thermoelectric generating device, heated by the flame of said main burner, for energizing said second valve means; the amount of energy produced by said first thermoelectric generating device being insufficient for both of said valve means, and the flame of said pilot burner being so small that it is incapable of effectively heating both of said thermoelectric generating devices; and means, movable in response to change in a condition resulting from the operation of said main burner, for controlling the energization of said valve means by said thermoelectric generating devices, and acting in its movement in one direction to first effect energization of said first valve means by said first thermoelectric generating device, and, by continued movement in the same direction to effect energization of said second valve means by said second thermoelectric generating device.

WILLIAM A. RAY.
